UNITED STATES PATENT OFFICE.

AUGUST FABER, OF OAKLAND, MAINE.

CARBURETOR.

Application filed July 15, 1924. Serial No. 726,152.

This invention relates to carburetors and has particular reference to an improved construction of venturi so as to insure a swirling action of the gas to bring about a more perfect atomization, a better combustion, and a minimum of fuel necessary to operate the engine.

A further object is to provide a venturi with inclined or tapering blades or vanes extending throughout its length and past the waistline of the venturi.

This invention is particularly designed as an improvement upon the construction set forth in my pending application, Serial No. 15 704,241, filed April 4, 1924.

With these and other objects in view, the invention consists in certain novel features of construction and combinations and arrangements of parts which will be more 20 fully hereinafter described and pointed out in the claim.

In the accompanying drawings—

Figure 1 is a view partly in section and partly in elevation illustrating my invention;

Figure 2 is a view in transverse section on the line 2—2 of Figure 1;

Figure 3 is a view in transverse section on the line 3—3 of Figure 1.

1 represents a carburetor of any approved construction, it being understood that the carburetor shown is for purposes of illustration only and specifically has nothing whatever to do with the invention except to 35 illustrate a simple form of carburetor in which my improved venturi 2 is located in the outlet passage 3 of the carburetor.

4 represents a nozzle having a suitable needle valve 5 which discharges the proper 40 amount of gasoline into the venturi 2. It will be noted that my invention is applied to a venturi which has a restricted diameter or waist 6; in other words, the venturi is narrowest at a point intermediate its ends 45 and flares outwardly toward both ends. The nozzle 4 terminates at a point approximately at the waistline of the venturi.

Inside of the venturi and fixed to the walls thereof I provide a circular series of inclined blades or vanes 7 which extend from one end to the other of the venturi past the waistline. These blades or vanes 7 are widest at their respective ends and narrowest at the waistline of the venturi so that their inner edges are comparatively in straight lines 55 and preferably these inner edges converge from the lower to the upper end of the venturi, as clearly illustrated in Figure 1.

By providing said blades or vanes extending throughout the length of the venturi 60 past the waistline, a swirling action is insured not only within the venturi but also as the gas leaves the venturi, and by reason of this action improved gas is insured with a minimum of fuel consumption.

It is of course to be understood that the invention is not limited to any particular number of blades or vanes, but I believe 65 three to be preferred number although this may be varied to suit the trade.

Various slight changes and alterations might be made in the general form of the parts described without departing from my invention, and hence I do not limit myself to the precise details set forth but consider 75 myself at liberty to make such slight changes and alterations as fairly fall within the spirit and scope of the appended claim.

I claim:

A carburetor including a venturi having 80 a restricted portion between its ends, a nozzle located centrally in the venturi and terminating at the restricted portion of the venturi, and a circular series of inclined straight blades projecting inwardly from 85 the wall of the venturi and throughout the length of the venturi, said blades being angularly disposed relative to the axis of the venturi and having straight inner edges spaced from the nozzle, the inner edges of 90 the adjacent blades converging from the lower to the upper end of the venturi.

AUGUST FABER.
